UNITED STATES PATENT OFFICE.

FRANK MITCHELL, OF HAMMERSMITH, LONDON, ENGLAND, ASSIGNOR, BY MESNE ASSIGNMENTS, TO ATLANTIC NATIONAL BANK, OF PROVIDENCE, RHODE ISLAND, A CORPORATION OF RHODE ISLAND.

TARGET-PRACTICE APPARATUS.

1,086,836.

Specification of Letters Patent.

Patented Feb. 10, 1914.

Application filed April 19, 1907, Serial No. 369,150. Renewed July 5, 1913. Serial No. 777,496.

To all whom it may concern:

Be it known that I, FRANK MITCHELL, a subject of the King of England, residing at Hammersmith, London, England, have invented certain new and useful Improvements in or Relating to Target-Practice Apparatus, of which the following is a specification.

The object of this invention is to construct improved apparatus for shooting practice in which any ordinary rifle or gun or other aiming member can be used exactly in the ordinary manner.

The improved apparatus is more especially adapted for use with a rifle, the present service weapon or any substitute being capable of use therewith.

The weapon may be used and held quite freely in any position exactly as in ordinary firing but without the necessity of using ammunition. The accuracy of the aim at the instant of the firing action taking place is indicated or recorded by electrical means, by the marking of a miniature target electrically or mechanically or in any other suitable way.

According to the present invention a light cord hereinafter called a "connector" is stretched from the gun to a small target or to some point in front of the gun and at a comparatively short distance from it so as to lie in a straight line from the point of attachment on the gun to that on the target or other point. A very light and almost invisible cord may be used such as strong thread. This is kept in tension by means of springs, weights or equivalents and may be so arranged that the distance from the gun to the target may be varied, the cord being in some cases extensible as by a length of elastic or by a weight passing over a pulley or by a spring so that the connector is kept under tension although the distance may be varied.

As the connector when in use always lies in a straight line from the bore of the gun to the target its angular relation to the axis of the gun varies according to the direction in which the gun is pointed. This angular variation of the gun in relation to the connector is taken advantage of according to this invention to effect audible or visible record of the aim at the moment of pulling the trigger. As an example, an electric bell may be sounded, a light shown, an indicator

moved or other like effects produced, a miniature target or the pencil or pricker or the like of such target may be moved for marking purposes, or, the connector may carry a pointer or pricker and the gun may carry a terminal board or miniature target holder, the action of firing causing the pointer or pricker to approach and mark or perforate the target. The arrangement is preferably such that when the gun is pointed exactly truly the pricker is in front of the center of the miniature target but any angular movement of the gun will alter the relative positions of the target and pricker or marker and thus make a record of the accuracy or inaccuracy of the aim.

The marking of the indicator card or miniature target may be effected by the electric current itself in any well-known way such for example as by causing the current to pass through chemically prepared paper or by the passage of a spark to perforate the target.

A further feature of the invention is that the movement of the gun relatively to the connector may be magnified say for example through the action of a pivoted rod and such magnified movement recorded.

In the accompanying drawings which illustrate various constructions of target-practice-apparatus all according to this invention, Figure 1 shows a gun, connector, and target ready for use, the connector being shown as entering a target box. Fig. 2 is an elevation partly in section of a gun showing an electric arrangement for indicating accurate aim by ringing a bell. Fig. 3 is a section of a part of a gun barrel with an arrangement for marking a miniature target inside the barrel. Fig. 4 is an elevation of a gun with a miniature target mounted outside and parallel to the barrel. Fig. 5 is a sectional elevation of a construction in which a miniature target is carried in a separate tubular holder capable of being slipped over the end of the gun barrel. Fig. 6 is an elevation of a form in which the miniature target is on the outside of a gun the direction of aim being indicated on an ordinary indicator. Fig. 7 is a face view of the miniature target shown in Fig. 6. Fig. 8 shows a portion of the gun barrel with a connector and magnifying rod. Fig. 9 is a sectional elevation showing a continuous flexible connector passing through a bent tube provided

with a pricker or marker. Fig. 10 is a dia-
grammatic view of an electro-chemical or
electric-spark marking-arrangement for the
miniature target.

5 Referring first to Fig. 1 it will be seen
that the gun 1 is connectively related to the
target 3 by a flexible connector 2. This con-
nector which may be of light thread, cord
or wire, is shown passing through the tar-
get which may have a hole in it for the
purpose and the connector is kept taut by
a drum and coiled spring inside the box
behind the target 3 the object being to give
a perfectly free gun which may be moved
10 about and held at different heights and dis-
tances from the target while still enabling
the connector to form a straight line to the
target. In this form the connector passes
up the bore and is attached to a plug in
15 the breech end 4 and is at that part only
permanently central with the bore. The
connector being very much smaller than the
bore it is possible to hold the gun pointing
toward the bull on the target with the cord
20 exactly in the center of the bore for its
whole length thus it will not touch the for-
ward part of the bore except when the gun
is put out of line which action is taken ad-
vantage of in various ways as will be here-
25 inafter described.

30 The gun may for example be arranged as
illustrated in Fig. 2 in which the flexible
connector 2 is attached to a plug 5 in the
breech end or cartridge chamber of the bar-
rel and passes to the target 3 and thence
35 over a drum. The connector 2 in this case
is a fine wire either entirely or for a length
somewhat greater than the barrel in which
case the remainder may be a fine cord or
40 strong thread shown kept under tension
over a drum by a weight 7 as shown in Fig.
2. The plug 5 may in this case be made of
rubber to insulate a wire which carries near
45 the forward end of the barrel a washer or
contact 8 and at the rear end passes through
the rubber plug and is provided with an
insulated extension to enable the plug to be
extracted.

50 In the forward end of the barrel is insert-
ed a metal ring 9 having preferably an in-
ternally coned surface surrounding the
washer 8 such ring being capable of longi-
tudinal adjustment in the barrel. Beneath
55 the barrel is a metallic insulated strip 10
connected to the metal portion of the con-
nector 2 at one end and at the other end to
the coil of a magnet 11 from whence a cir-
cuit passes to a bell terminal and through
60 a battery 12 to a spring 13 on the trigger
guard from which it is insulated there be-
ing a branch circuit from the armature 14
of the magnet to the trigger and a connec-
tion from a contact piece 15 to the other bell
terminal.

65 The action is as follows:—Upon pulling

the trigger the bell and battery circuit will
be momentarily closed at 13 and the bell
will ring if the washer 8 is not in contact
with the coned ring 9. If however at that
instant the washer 8 is in contact with the
70 adjustable cone 9 through the gun being
pointed slightly out of line, then the current
from battery 12 will be shunted and passes
thence into the barrel from the barrel to
washer 8 and wire connection with the insu-
lated wire strip 10 to the magnet 11 on to
the battery 12. Owing to there being con-
tact between the washer 8 and the cone 9
the circuit will be made and the magnet
will now lift the armature 14 and break
80 the bell circuit so that the bell will not ring
and it will be known that the gun has been
incorrectly aimed. In place of the bell any
other electrically controlled method of in-
dicating may be adopted and the coned ring
85 95 may be built of insulated segments so that
by closing different electric circuits accord-
ing to which part of the cone is touched by
the washer 8 an indication as to which side
the fault of aim is may be obtained. Or
90 the washer may be made of insulated seg-
ments instead of the cone for the same pur-
pose. The object of the cone shape of the
ring is that by shifting the part farther in
or out the aim will require to be more or less
95 accurate as desired.

100 In the form shown in Fig. 3, 17 is a uni-
versally pivoted rod or lever forming the
end of the connector which latter is at-
tached to the target in any suitable way.
105 The rod or lever 17 in the form shown is
pivoted in a plug 18 held tight in the for-
ward part of the barrel while its inner end
19 carries or forms a pointer or marker. In
this case there is an indicator card or mini-
ature target holder 20 mounted on a spring
110 or elastic plug which may be similar to that
shown in Fig. 2; this holder 20 is placed
normally just out of reach of the pointer or
marker 19. The holder 20 is carried by a
pin 21 which passes through the plug and
115 projects at the breech end. When such a
plug is put in a central fire gun no special
mechanism except that already provided in
the gun is required to give the desired move-
ment for perforating or marking the mini-
ature target, as the action of firing will drive
120 the pin 21 and holder 20 forward owing to
the firing needle striking it in the same man-
ner as it would strike an ordinary cartridge,
a record being thus made on the target card
corresponding to the angular or other pos-
125 ition taken up by the pointer 19 as the re-
sult of the aim. The plug in this case be-
ing made of rubber will again pull the mini-
ature target in the holder 20 away from
the pointer 19 when the bolt is pulled back
130 ready for firing again, thus the operation
can be repeated showing a number of rec-
ords on one indicator card or miniature tar-

get, or the plug can be extracted and each record examined or a new target card inserted. It will be obvious that the plug may contain or be substituted by any spring 5 means for withdrawing the target holder or that the pin 21 may act as the pointer and the target holder be carried on the rod 19.

In the form shown in Fig. 4, the indicator card or miniature target holder 20 is 10 mounted on a rod 22 slidably mounted on the outside of the gun and parallel with the barrel, such rod 22 being mechanically connected to the firing needle bolt head 24 so that upon firing action taking place it 15 gets a forward jump or push by the said bolt head sufficient to allow a pointer or needle carried or moved by the connector to prick or mark the target. To enable this to be done the pricker or marker 25 is shown 20 mounted on the connector 2. The connector 2 in this case passes up the bore and the indicator card or target holder 20 is cranked or held over so that it is concentric with the bore. The rod 22 is shown as provided with 25 a spring 23 to keep the target normally away from the pricker or marker. Or such a connector may be connected to the firing pin bolt head direct. In this manner it would also get the necessary forward jump 30 due to the elastic pull of the cord to prick or mark a stationary miniature target mounted on the gun.

In the form shown in Fig. 5 the miniature target or target holder 20 is carried by 35 a separate barrel 26 adapted to be placed on the gun barrel. As shown the rod or lever 17 is pivoted at 18 to the plug pin 21 and carries at its outer end the pricker or marker 25 which is normally held from 40 contact with the miniature target by the action of spring 27 in plug 5. The connector is shown kept under tension by a coiled spring behind the target.

In Fig. 6, the miniature target 20 has a 45 series of separate contact plates (see Fig. 7) each connected to an ordinary room indicator, the central one being in connection with the bell as is also the rod or lever 17 the arrangement being such that when 50 the miniature target is brought in contact with the lever 17 on firing the gun the circuit is completed and the indicator will show the direction of the aim at the moment of firing. The connector as shown being 55 partly elastic is connected to a hook on the target.

Fig. 8 illustrates a construction in which the rod 17 does not form part of the connector 2 but is operatively connected there- 60 to as at 28, the connector itself passing straight down within the bore of the gun and being connected centrally at the breech- end. The rear end of the pivoted rod 17 is provided with a pointer or marker as in 65 the construction illustrated in Fig. 6, and a

marking or miniature target is provided mounted upon the gun working in conjunction therewith. The advantage of this construction is that the relative motion which occurs when there is want of alinement between the axis of the gun and the connector 70 2 owing to inaccurate aim is magnified and such magnified movement recorded.

In the form shown in Fig. 9, a cord 17 is connected at one end to a plug 5 similar 75 to those already described at the breech-end of the barrel; it then passes through a bent tube 18 which carries a pricker or marker 19 at the forward end of the gun and is connected to the objective target so as to be kept under tension as described, the action 80 of recording being the same as already described. This bent tube 18 carrying the marker 19 forms a very convenient adjustment for the distance between the miniature 85 target and the marker, for if the connector 17 be slackened, the bent tube can be shifted along the wire forming the connector to make such alteration, but when stretched taut, the friction between the wire and the 90 tube at the bends is sufficient to keep the connector and the tube in fixed relationship.

Fig. 10 indicates how a record may be 95 made on the chemically prepared paper or like material of which the miniature target 20 may be made. As shown, the bent rod 17 and the connector 21 carry metal points 18 and 19 the latter being connected by the wires shown, one to one pole and the other to the other pole of an electric battery not shown. With such construction the act of 100 firing would close the circuit, and the current passing through the paper would leave a mark or point, or if a coil be used, the same action may cause a spark to perforate 105 the paper target by passing between the points 18 and 19, the mark or perforation showing the accuracy of the aim.

It will be observed that the connector in 110 each case constitutes a director or controller, directing or controlling the movement of the recording member and causing its relation to the target to correspond to the deviation of the line of sight of the aiming device from the bullseye of the main target. 115

What I claim as my invention and desire to secure by Letters Patent is—

1. In a target practice apparatus the combination with an aiming device and a target to be aimed at of a movable connector joining the aiming device, and a point fixed relatively to the target, and a recording member for recording deviations of the line of sight of said aiming device from the target, said recording member being connected to 120 said connector to be controlled thereby.

2. In target-practice apparatus the combination of an aiming device, a target to be aimed at, a flexible rectilinear movable connector stretched between the gun and a 130

point fixed relatively to the target, and means acting through the movement of said connector for reproducing any movement from the normal alinement between the gun 5 and the connector.

3. In a target-practice apparatus the combination of an aiming device, a target to be aimed at, a connector stretched between the aiming device and the target, means for 10 keeping such connector in tension and allowing for variation in the distance between the aiming device and the target, and trigger-controlled means for recording any movement from the normal alinement between the 15 aiming device and the connector.

4. In a target-practice apparatus the combination of an aiming device, a target to be aimed at, a connector stretched between the aiming device and the target, a weight and 20 pulley near the target for keeping such connector in tension and allowing for variation in the distance between the aiming device and the target, and trigger-controlled means for recording any movement from the 25 normal alinement between the aiming device and the connector.

5. In a target-practice apparatus the combination of an aiming device, a target to be aimed at, a rod pivotally mounted on the 30 aiming device, a connector joining the rod and the target, a miniature or marking target carried by the aiming device, and trigger-operated means for bringing the marking target and the rod into temporary contact.

6. In target-practice apparatus the combination of an aiming device, a target to be aimed at, a connector joining the aiming device and the target, a miniature or marking 40 target supported on the aiming device, a marker on the connector, and trigger-operated means for bringing the marker and the miniature target into temporary contact.

7. In target-practice apparatus the combination of an aiming device, a target to be aimed at, a rod pivotally mounted on the aiming device, a connector between the rod and the target, an operative connection between the connector and the rod, a marking 50 or miniature target mounted on the aiming device, and trigger-operated means for bringing the miniature target and the rod into temporary contact.

8. In target-practice apparatus the combination of an aiming device, a target to be aimed at, a flexible connector having one end attached to the aiming device and the other passing through the target to be aimed at, a weight-operated drum near the target 60 acting to keep the connector in tension, a marker on the connector, a miniature or marking target carried by the aiming device.

vice, and trigger-operated means for bringing the marker and the miniature target into temporary contact.

9. In target-practice apparatus the combination with an aiming device, of a miniature or marking target supported by the aiming device, and means also supported by the aiming device for recording upon the miniature target the direction of aim.

10. In a target practice apparatus the combination with an aiming device for aiming at a reference object, said device being free from any mechanical support and used 75 without ammunition, of means for indicating the direction of aim, and means connectively relating the aiming device to the object aimed at and controlling the aim indicating means.

11. A target practice apparatus having an aiming device, a target, a target-recording means actuating means therefor, and a flexible rectilinear recorder controlling connection between the aiming device and said target serving to control the position of the recording means through the movements of the aiming device.

12. The combination with an aiming device, of a follower carried by the aiming 90 device for recording the aim thereof, a director engaging the follower and being fixed with reference to a point extraneous to the aiming device.

13. In a miniature target practice apparatus the combination with an aiming device of a flexible connector normally in line with the bore thereof and connected thereto, and a recording member attached to said connector.

14. In a miniature target practice apparatus the combination with an aiming device having a barrel of a recording member, a flexible connector operatively connected to the recording member and to the aiming device, and passing into the barrel of the aiming device.

15. In an apparatus for recording the direction of aim of an aiming device the combination with a flexible connection extending 110 from the aiming device to a point fixed with relation to the object aimed at, and means controlled by the relative deflection between said connector and said aiming device for recording the direction of aim at the movement of firing.

In testimony whereof I have signed my name to this specification in the presence of two subscribing witnesses.

FRANK MITCHELL.
